UNITED STATES PATENT OFFICE

ADOLF LANGE, OF LUBECK, GERMANY, ASSIGNOR TO LÜBECKER MASCHINENBAU-
GESELLSCHAFT, OF LUBECK, GERMANY

TRACK-CHAIN BOGIE OF CARRIAGES

Application filed September 24, 1929, Serial No. 394,908, and in Germany October 22, 1928.

My invention relates to track-chain bogies of carriages or cars with two or more track-chain guiding frames, and more particularly to an improved controlling mechanism for or 5 in connection with the bogie or truck.

Track-chain bogies or trucks of the kind referred to are capable of swinging in two planes in case of running over uneven ground so that with the controlling means as hitherto used the swinging movement of the track-chains in the one plane only can be balanced, while the controlling means necessarily must follow the oscillation or swinging movement of the track-chains in the other plane so as to 10 have some effect on the moving direction of the bogie or truck.

According to the present invention, the track-chain bogie or truck supported by a spherical member is provided with a lever 20 mounted on the bogie frame supporting the load so as to transmit the weight thereof to the guiding frame of the track-chains, the said lever being adapted to be turned about a horizontal axis passing through the centre 25 of the said spherical supporting member, and having its free end shaped to form a head or pin for the controlling rod or rodwork to engage therewith, the construction and arrangement of the parts being such that the 30 centre line or axis of the pin will also pass through the centre of the said spherical supporting member.

In case of a bogie or truck of the character set forth and provided with diagonal or universal joint supports intermediate between the load frame and the bogie frame, the centre 35 lines of the swinging axis of the lever and of axis of the pin will coincide, according to the present invention, with the corresponding centre lines of the axes of the universal joints. In lieu of the pin, however, any other suitable means such as a ball-joint or the like may be provided for the engagement with the controlling rod or rodwork. 40

By constructing the controlling mechanism in the manner herein set forth the point of engagement or connection between the controlling rod or rodwork and the lever will not 45 and cannot change its position with relation

to the body of the car, when the bogie frame is accidentally caused to swing.

I will now proceed to describe my invention more in detail in connection with the embodiment thereof illustrated somewhat 55 diagrammatically on the accompanying drawings, it being intended and understood that the invention is illustrated by, but not limited to the embodiment thereof so illustrated and described.

In the accompanying drawings forming a part of this specification and illustrating for purposes of exemplification, a preferred form and manner in which the invention may be embodied and practised, but without limiting the claimed invention to such illustrative instance:

Figure 1 is a view in front elevation of a track-chain bogie or truck having two track-chain guiding frames, and Figure 2 is a view 70 in top plan thereof.

In the embodiment shown the two track-chains *a* are interconnected by axles *b* with the bogie frame *c* mounted thereon in the usual manner. Track-chain guides frames *b'* are provided within the track-chains *a* in such manner that the chains *a* are supported and guided thereby as they travel about, said frames *b'* also having the axles *b* mounted therein. Each bogie frame *c* is supported 75 by at least two track-chain guide frames *b'* and the corresponding track-chains *a*. The bogie frame *c* carries, at a point midway between its two ends, a boss *d* having a spherical surface for the load frame *e* to be supported 80 thereby. The extremities of the two shanks of the forked lever *f* are pivotally connected with the bogie frame *c* by means of horizontal pins *g* so that the lever can be turned or 85 swung about the common axis *h* of the two pivots or pins *g* passing through the centre of the spherical boss *d* and which may, as shown in the embodiment illustrated, lie in the running direction of the car.

The free end of the lever *f* is shaped to 90 form a head or pin *i* for connection with the rodwork of the controlling mechanism. The median line *k* of the lever, that is, the axis of the pins *i* also goes through the centre of the spherical boss *d* and crosses the axial 100

line *h* at right angles. Whenever the chains run over uneven ground so that the bogie will be caused to swing in the one or other direction, the head or pin *i* will remain stationary all times inasmuch as it cannot change its position with relation to the load frame.

What I claim is:—

1. In an arrangement of the character described of the type having a bogie frame situated under and universally connected to the load frame and wherein at least two track-chain guide frames support the bogie frame, a forked controlling lever having the ends of its branches pivotally connected to the bogie frame at points on opposite sides of the universal connection in such manner that the longitudinal axes of such pivot points coincide with the corresponding longitudinal axis of the universal connection, and a head pin on the main end of the lever adapted for association with the controlling mechanism of the car and having its longitudinal axis coinciding with the corresponding moving axis of the universal joint and intersecting the axes of the pivotally connected branches.

2. In a carriage of the type described, the combination, a main load frame; a bogie frame for association with the main load frame, at least two track-chain guide frames supporting the bogie frame, a forked lever having the ends of its branches pivotally connected to the adjacent bogie frame, a head pin adapted for association with the controlling mechanism of the carriage at the outer end of the lever, and a spherical member on each bogie frame supporting the load frame and situated at the intersecting point of the longitudinal axes of said pivotally connected forked branches and said head pin.

In testimony whereof I have signed my name to this specification.

ADOLF LANGE.

line *h* at right angles. Whenever the chains run over uneven ground so that the bogie will be caused to swing in the one or other direction, the head or pin *i* will remain stationary all times inasmuch as it cannot change its position with relation to the load frame.

What I claim is:—

1. In an arrangement of the character described of the type having a bogie frame situated under and universally connected to the load frame and wherein at least two track-chain guide frames support the bogie frame, a forked controlling lever having the ends of its branches pivotally connected to the bogie frame at points on opposite sides of the universal connection in such manner that the longitudinal axes of such pivot points coincide with the corresponding longitudinal axis of the universal connection, and a head pin on the main end of the lever adapted for association with the controlling mechanism of the car and having its longitudinal axis coinciding with the corresponding moving axis of the universal joint and intersecting the axes of the pivotally connected branches.

2. In a carriage of the type described, the combination, a main load frame; a bogie frame for association with the main load frame, at least two track-chain guide frames supporting the bogie frame, a forked lever having the ends of its branches pivotally connected to the adjacent bogie frame, a head pin adapted for association with the controlling mechanism of the carriage at the outer end of the lever, and a spherical member on each bogie frame supporting the load frame and situated at the intersecting point of the longitudinal axes of said pivotally connected forked branches and said head pin.

In testimony whereof I have signed my name to this specification.
